UNITED STATES PATENT OFFICE.

VICTORIO BRAZZOLA, OF BUENOS AIRES, ARGENTINA.

LOCOMOTIVE USING CRUDE FUEL OIL.

Application filed September 30, 1922, Serial No. 591,655, and in Argentina June 27, 1922.

This invention relates to certain new and useful improvements which I have introduced into the method of combustion actually employed in locomotives using crude oil as fuel. By means of these improvements, besides a uniform and constant working, the total consumption of the gases in the fire box, and, consequently, a maximum of heating power is obtained from the fuel.

5 By the use of the actual method of firing in which combustion is obtained by an intermittent draft produced by the operation of the exhaust pipe, arranged within the smoke box, the process of combustion cannot 10 take place in a convenient manner as regards the complete utilization of the gases, as it allows of a high percentage of these latter to get carbonized and be exhausted without having been burnt or having been so only 15 in an imperfect manner.

A further advantage offered by my present invention, consists in avoiding the carbonization of the oil in the valves and cylinders, caused by the hot gases of the smoke box, 20 because, as in accordance with my invention the exhaust pipes are arranged to exhaust outside said smoke box, the vacuum caused by the movement of the plunger, will be replaced by atmospheric air, thereby eliminating 25 the drawback of the carbonization of the oil.

In order that my invention may be more readily understood, an illustrative drawing has been annexed to this specification, showing 30 in front elevation the ordinary arrangement of the steam and exhaust pipes of a locomotive. In the same figure and by means of pointed lines, the novel arrangement of said parts in accordance with my invention 35 has been indicated. It should however be understood that the exhaust may be led in any other direction, outside the smoke box, without such alteration of the direction affecting the scope of this invention.

40 The invention substantially consists in so arranging in any suitable manner the exhaust pipes that they allow of deviating, outside the smoke box, the steam used in the cylinders and applying a continuous draft 45 to the combustion by means of the existing draft producing apparatus, usually known as blower. It will be evident that this blower or draft producing apparatus may be subjected, if deemed necessary or convenient, 50 to certain accidental modifications, in accordance with the force of draft required,

without affecting the essential part of the invention.

In said drawing, 1 indicates the draft producing apparatus or blower which according to the prior method, is mounted on the nozzle of an exhaust pipe which terminates somewhat below the illustrated position of said blower and which discharges in the interior of the smoke box. Now, in accordance with my invention, the exhaust pipes have been provided with the extensions 3, 3 and 4, 4, so that the discharge will take place outside the smoke box. The usual interiorly exhausting pipe is thus eliminated and the necessary support for the blower is obtained by conveniently arranging a strong supporting plate 5, secured in position in any suitable way. In the known arrangement, said blowing device is fed not only by the exhaust, 70 which causes the same to operate in an intermittent manner, but also, while the engine is stopping, with steam from a steam pipe 6, liable to become obstructed or get out of order. In order to avoid such objection, I provide a second or supplementary pipe 7 which only operates when the main pipe 6 gets out of order, thereby avoiding the necessity of repairs and a considerable loss of time during operation. Said pipes may be 75 obturated at will by means of the cocks 8.

From the foregoing it will be seen that the improvements in accordance with my invention may be readily introduced into the existing arrangements, at a small cost.

80 In the drawing, the bifurcated pipe, 4 has been so arranged that the union or joined part of both branches is located at the upper part of the smoke box, both said branches there communicating with a pipe or stack 90 discharging outside the smoke box, to atmosphere. Said point of junction may however be situated at any other suitable part of the smoke box without impairing the satisfactory working of the arrangement in any 95 way.

Having now particularly described and ascertained the nature of my said invention and in what manner the same is to be performed, I declare that what I claim, is:—

105 In an oil-burning locomotive, in combination, a smoke stack; a smoke box; steam exhaust pipes leading from the cylinders, entering the smoke box at its lower portion, one at each side of the vertical center line, 110 extending substantially vertically upwardly through the smoke box at opposite sides

thereof to points above its transverse center line, converging and uniting at the top center region of the smoke box and there having closed communication with said stack to discharge the steam to atmosphere outside the smoke box; a transverse plate at approximately mid-height in the smoke box; a blower supported on said plate and communicating with the smoke stack; a main pipe 6 for conducting steam from the sup-

ply to said blower during normal functioning of the parts; a valve for controlling the flow of steam in said pipe; and a supplemental valve-controlled pipe 7 inoperative during proper functioning of said main pipe 15 but operable alternatively thereto in the event of failure of the latter to function.

In testimony whereof, I have signed my name to this specification.

VICTORIO BRAZZOLA.
